TAPE RECORDER

Sheldon Lee Pastor, Chicago, and Robert L. Deschamps,
West Chicago, Ill., assignors to Minnesota Mining and
Manufacturing Company, St. Paul, Minn., a corpora-
tion of Delaware

Filed Dec. 13, 1962, Ser. No. 72,828

Term of patent 14 years

(Cl. D26—14)

FIG. 1

FIG. 2

FIGURE 1 is a top, front and left side perspective view of a tape recorder, showing our new design; and

FIGURE 2 is a top, front and right side perspective view thereof.

The dominate features of our design are shown in solid lines in the accompanying drawing. The speaker grills are continuous over the areas outlined in each side of the recorder. The rear and bottom are free of ornamentation.

We claim:

The ornamental design for a tape recorder, substantially as shown and described.
